UNITED STATES PATENT OFFICE.

MARZ F. ROCHESTER, OF INGLESIDE, MARYLAND.

PHARMACEUTICAL IMPLEMENT.

SPECIFICATION forming part of Letters Patent No. 693,156, dated February 11, 1902.

Application filed March 28, 1901. Serial No. 53,231. (No model.)

To all whom it may concern:

Be it known that I, MARZ F. ROCHESTER, a citizen of the United States, residing at Ingle-
5 side, in the county of Queen Anne and State of Maryland, have invented new and useful Improvements in Pharmaceutical Imple-
ments, of which the following is a specifica-
tion.

This invention relates to pharmaceutical instruments; and the primary object thereof is to provide an improved device of the character described which will be applicable to various uses; and with this object in view the invention consists in the parts and combina-
10 tions of parts, all of which will be fully de-
scribed hereinafter, the novel features recited in the claims, and the construction illustrated in the accompanying drawings, in which—

Figure 1 is a side elevation of the invention with the parts folded upon each other. Fig. 2 is a top plan view showing the parts in their extended position.

Referring now to the drawings by numerals of reference, 1 designates an imperforate spoon-shaped blade, from one end of which projects an elongated handle 2. Hinged to the extreme end of this blade is a similar handle 3 of a perforate spoon-shaped blade 4, from the bottom of which projects a funnel-
15 shaped extension 5. Near the juncture of the handles 2 and 3 with the respective spoon-shaped blades I provide blocks 6 and 7. At or adjacent the hinge 8 are pivoted a corkscrew and knife-edged lever 9 and 10, respec-
20 tively, the lever 10 having a right-angle exten-
sion 11 for severing the wire fasteners upon bottles and for other purposes. The extension 11 is adapted to fit into a notch 7 when the blades are closed together. On one
25 edge of the blade 3 I provide a longitudinally-
extended right-angular flange 12, while a simi-
lar flange is arranged on the opposite edge of the blade 2 and designated by the reference-
30 numeral 13. Under normal conditions and when not in use the device will be folded, as shown in Fig. 1, the flanges 12 and 13 inclos-
ing the lever 10 and the corkscrew 9, thereby
protecting the same from contact with dirt,
dust, or other foreign substances. The points
35 of the lever 10 and the corkscrew 9 will be held within the resilient blocks 6 and 7 and will thereby be protected. It will be noticed

that when folded the spoon-shaped blades register at their respective edges, so as to form an inclosed receptacle.

In actual practice the device will be ex-
tended, as shown in Fig. 2. If it is desirable to remove a cork from a bottle, the lever 10 will be utilized for removing the wire or other fastening and the corkscrew for removing the cork. In measuring the doses it frequently happens that more than the required amount is poured in the graduate. If an excessive amount is dispensed into the blade 1 and it is desirable to return the medicine to the bottle, 60 this can be easily done by folding the handles 2 and 3 upon each other, as shown in Fig. 1. In this operation the blade 4 should be folded upon the blade 1, and the receptacle formed thereby should be inverted, so as 65 to bring the funnel 5 in the position to be inserted in the neck of the bottle. The contents of the receptacle thus formed will there-
by enter the bottle by force of gravity.

In the foregoing it will readily be seen that 75 I have provided a cheap, durable, and effi-
cient device of the character described, and by its use I dispense with a plurality of tools or implements which would otherwise have
70 to be employed.

I have described in detail what to me at this time appears to be the very best means of accomplishing the desired result, although I would have it understood that I do not limit myself to the exact details of construction 85 shown. For instance, the blades 1 and 4 might be of various shapes to suit existing circumstances or I might graduate the con-
cave surface of the blade 1 without affecting the utility of the invention.

What I claim, and desire to secure by Let-
ters Patent, is—

1. A pharmaceutical instrument comprising an imperforate concavo-convex blade, and a perforated concavo-convex blade provided 95 with a funnel-shaped extension, an elongated handle for each of said blades, said handles having a hinged connection and being adapt-
ed to be folded together.

2. In a device of the character described, 100 the combination with an imperforate con-
cavo-convex blade, and a perforated concavo-convex blade; of an elongated handle pro-
jecting from each blade and hinged together,

whereby the two blades may be folded one upon the other, so that their edges meet.

3. In a device of the character described, the combination with an imperforate concavo-convex blade, and a perforated concavo-convex blade; of an elongated handle projecting from each blade, and hinged together whereby the two blades may be folded one upon the other, so that their edges meet; and

longitudinally-extending flanges on the respective handles for the purpose described.

In testimony whereof I affix my signature in presence of two witnesses.

MARZ F. ROCHESTER.
